UNITED STATES PATENT OFFICE

143,822

DESIGN FOR AN AIRPLANE

Clarence L. Johnson, Encino, Calif., assignor to
Lockheed Aircraft Corporation, Burbank,
Calif.

Application June 5, 1944, Serial No. 113,858

Term of patent 14 years

(Cl. D71—1)

To all whom it may concern:

Be it known that I, Clarence L. Johnson, a citizen of the United States, residing at Encino, in the county of Los Angeles and State of California, have invented a new, original, and ornamental Design for an Airplane, of which the following is a specification, reference being had to the accompanying drawings, forming a part thereof:

Figure 1 of the drawings is a perspective view of an airplane embodying the new design as it would appear from a point off to the side and slightly forward and above the airplane while in

flight with its main and nose landing wheels retracted;

Figure 2 is a side elevational view of the subject airplane with landing gear extended;

Figure 3 is a top plan view thereof;

Figure 4 is a front elevational view thereof with landing gear extended.

I claim:

The ornamental design for an airplane, substantially as shown.

CLARENCE L. JOHNSON.
